BARNETT I. HORWITZ, OF DENVER, COLORADO.

PROCESS FOR MAKING CIGAR-TIPS.

1,226,074.

Specification of Letters Patent. Patented May 15, 1917.

Application filed April 19, 1915. Serial No. 22,285.

To all whom it may concern:

Be it known that I, BARNETT I. HORWITZ, a citizen of the United States, residing in the city and county of Denver and State of Colorado, have invented certain new and useful Improvements in Processes for Making Cigar-Tips; and I do declare the following to be a full, clear, and exact description of the invention, such as will enable others skilled in the art to which it appertains to make and use the same, reference being had to the accompanying drawings, and to the characters of reference marked thereon, which form a part of this specification.

15 My invention relates to an improved process for making cigar tips or mouth pieces, my object being to provide a sanitary sealed covering for the mouth piece end of the cigar, which may be applied thereto at 20 the time the cigar is manufactured, and held in place by the band which is to be employed in connection with the cigars provided with these tips.

The tip is preferably made from cork paper to which a piece of paraffin paper is also applied. These two layers when properly connected, are cut to form semi-circular blanks, or the cork paper and paraffin paper may be cut separately to form 30 blanks of corresponding size, after which they are connected in such a manner as to form a substantially integral fabric, the cork paper being on one side and the paraffin paper on the other side. The blank is then 35 bent to form a hollow cone approximately, with the paraffin paper on the inside, care being taken to leave a small orifice at the end of the tip on one side. This article is then placed in a die or female member having a 40 cone shaped socket, which is the counterpart of the cone shaped tip. A male member of corresponding shape and adapted to engage the tip on the inside is then applied, being heated sufficiently to melt the paraffin forming the lining of the tip, which melted paraffin runs down and forms a thin film over the aperature left in the tip or mouth piece at the time of the forming of the tip, as heretofore explained. The tip is then 45 complete, and will drop without difficulty out of the mold or female member of the device.

Having briefly outlined my improvement, I will proceed to describe the same in detail, reference being made to the accompanying

drawing, in which is illustrated an embodiment thereof. In this drawing,

Figure 1 is a view of the blank from which my improved tip is made, showing the cork paper layer partly broken away.

Fig. 2 is an elevation of the complete tip.

Fig. 3 is a sectional view of the device employed in producing the tip.

Fig. 4 is an elevation of a cigar before the tip is applied.

Fig. 5 is a similar view with the tip in place.

Fig. 6 is a view of the same, but showing the fastening band applied.

Fig. 7 is a similar view showing the label side of the band.

The same reference characters indicate the same parts in all the views.

Let the numeral 5 designate the blank which preferably consists of a layer of cork paper 6 and a layer of paraffin paper 7. 75 This sheet of cork and paraffin paper is cut into semicircular form, approximately, after which it is bent to form substantially a hollow cone which is then inserted in the recess or cavity 8 of the block or female member 9. 80 The male member 12 of the device whose extremity 10 is of counterpart shape, is then applied to the paraffin surface of the hollow cone shaped article, and pressed firmly against the same. This male member of the 85 forming device may be heated in any suitable manner. As shown in the drawing, this last named member is heated by the electric current, a resistance coil 13 being inserted in the cavity 14 of the male member, which is 90 formed hollow for the purpose. One extremity of this coil merges into an electrode 20 which is connected with an electrical conductor 15 which leads to one pole of the electrical source; while an electrode 16 is connected with the opposite extremity of the coil which is located in the inner extremity of the male member as shown at 17. The electrode 16 is connected with an electrical conductor 18, which leads to the other pole 100 of the circuit. The two electrodes 16 and 20 are mounted in a block 21 which is screwed into the outer extremity of the male member of the device. Where the tips are made by hand, the upper portion of the male member 12 should be protected by a covering 22 of insulation.

As the heated male member is applied to

the paraffin surface of the tip as heretofore explained and the film of paraffin is melted, it not only runs down and closes the opening 23 at the pointed end of the tip, but it also 5 seals the overlapped portion of the tip, which is indicated by the lines 24 and 25 in Figs. 2, 5 and 6 of the drawing.

The tip is then removed from the female member of the device, and is ready to be 10 applied to the extremity 26 of the cigar. The latter then presents the appearance illustrated in Fig. 5. A band 27 may then be applied to the cigar in such a manner as to overlap the tip at the larger extremity 15 thereof, whereby it is adapted to hold the latter securely in place. This may be the band carrying the trade-mark or any suitable legended-device or design which it may be desirable to place upon the band to be 20 used.

My improved tip which may be designated by the numeral 28, when completed, is provided with a thin film of paraffin 29 which closes the aperture 23 as heretofore explained. This film is readily soluble and if it is desired to keep the tip end of the cigar in the mouth a short time before lighting the cigar, this film or seal will dissolve, leaving an opening for the passage of the 30 smoke. However, if it is desired to light the cigar immediately, the blaze of the match before applying it to the lighting end of the cigar, may be touched to the paraffin film 29, which will instantly melt without 35 injuring the rest of the tip in any way. The match is then applied to the opposite end of the cigar and the smoker draws on the tip end, when the smoke passes through the opening 23 without cutting off the pointed 40 end of the cigar or changing the latter in any way except as heretofore described. Of course, the device employed in covering the tips may be of any suitable construction, and the male member thereof may be heated in 45 any suitable or desirable manner.

Attention is called to the fact that the film or seal 29 for the aperture 23 of my improved tip or mouth piece, may be broken in any suitable manner. In other words, it 50 must be understood that while this fragile seal or film is both soluble and meltable, it is not necessary to employ either heat or moisture in order to break it, since it may be broken by the use of a tooth pick or other 55 small or readily available instrument, as soon as the smoker gets ready to light the cigar.

Having thus described my invention, what I claim is,—

60 1. The herein described process of producing a tip or mouth piece for cigars, con-

sisting in coating a blank with paraffin or similar substance, bending the blank into tip form with the paraffin surface innermost, causing parts to overlap so as to leave an 65 aperture adjacent the point of the tip, and finally heating the inner surface to cause the paraffin to melt and close the said aperture and seal the overlapping portions of the blank.

2. The herein described process of producing a tip or mouthpiece for cigars consisting in coating a blank with paraffin or similar substance, bending the blank into tip form with the paraffin surface innermost, causing parts to overlap, and finally heating the inner surface to cause the paraffin to melt and seal the overlapping portions of the blank.

3. The herein described process of producing a tip or mouthpiece for cigars consisting in coating a blank with paraffin or similar substance, bending the blank into tip form with the paraffin surface innermost, causing parts to overlap so as to leave 85 an aperture adjacent the point of the tip, and finally heating the inner surface to cause the paraffin to melt and close the said aperture.

4. The herein described process of producing a tip or mouthpiece for cigars, consisting in coating a blank with paraffin or similar substance, bending the blank into tip form with the paraffin surface innermost, causing parts to overlap, and finally 95 heating the inner surface to cause the paraffin to melt.

5. The herein described process of producing a tip or mouthpiece for cigars, consisting in coating a blank with paraffin or 100 similar substance, bending the blank into tip form with the paraffin surface innermost, causing parts to overlap so as to leave an aperture adjacent the point of the tip, and finally heating the inner surface to cause the 105 paraffin to melt and seal the overlapping portions of the blank.

6. A process of producing a tip or mouthpiece for cigars consisting in coating a blank with an adhesive substance, bending the blank into tip form with the coated surface innermost, causing parts to overlap and finally heating the adhesive to cause it to melt and seal the overlapping portions of the blank.

In testimony whereof I affix my signature in presence of two witnesses.

BARNETT I. HORWITZ.
